UNITED STATES PATENT OFFICE.

AXEL H. HELANDER, OF PITTSBURG, PENNSYLVANIA, ASSIGNOR TO MESTA MACHINE COMPANY, OF PITTSBURG, PENNSYLVANIA, A CORPORATION OF PENNSYLVANIA.

BAROMETRIC CONDENSER.

No. 908,405.

Specification of Letters Patent.

Patented Dec. 29, 1908.

Application filed May 2, 1908. Serial No. 430,501.

To all whom it may concern:

Be it known that I, AXEL H. HELANDER, of Pittsburgh, Allegheny county, Pennsylvania, have invented a new and useful Barometric Condenser, of which the following is a full, clear, and exact description, reference being had to the accompanying drawings, forming part of this specification, in which—

10 Figure 1 is a vertical section partly broken away of a barometric condenser embodying my invention; and Fig. 2 is a similar view of a portion of the condenser showing a modified construction.

15 My invention has relation to the class of barometric condensers, and is designed to provide a novel arrangement of the steam pipe which carries the steam to be condensed into the condenser.

20 Heretofore it has been the practice to bring the steam pipe into the condensing chamber through the side wall of the same. This practice has necessitated the use of at least two large elbows in the steam pipe resulting in increased friction on the steam 25 and also increasing the expense of construction, these steam pipes being often of large diameters.

According to my invention, I extend the 30 steam pipe vertically into the condensing chamber, its upper end terminating within said chamber preferably at a point below the water inlet and provided with means of suitable character for preventing a discharge of the water into the pipe. This 35 not only effects a saving of at least one elbow in the steam pipe, but it also enables the steam pipe to be used as a support for the condenser when desired.

40 The precise nature of my invention will be best understood by reference to the accompanying drawings, in which I have shown two different embodiments thereof, it being premised, however, that various 45 other modifications may be made therein by those skilled in the art without departing from the spirit and scope of my invention as defined by the appended claims.

Referring first to the construction shown 50 in Fig. 1, the numeral 2 designates the condensing chamber having an inlet opening at 3 for connection with the usual water-supply pipe and an opening 4 at its upper end for connection with the exhaust or vacuum pipe.

55 5 and 6 designate interior cones and cups, or

baffles, arranged to produce a spraying action of the water discharged into the chamber at the opening 3. Any suitable arrangement of these baffles may be employed. In the arrangement as shown the water entering at the opening 3 flows over the upper end of the upper cone 5; thence downwardly into the cup below the top opening in said cone and over the edges of the cup into the lower cup 6 over the edges of which it is discharged. 7 designates the steam inlet pipe, which forms a vertical column upon which the condenser is supported, and which extends upwardly into the lower portion of the condensing chamber, terminating in a slotted or perforated head 8 through which the steam is discharged, this head being closed at its upper end to prevent the direct discharge of water therein. 9 designates the tail pipe connected with the lower portion of the chamber 2, and which discharges into the well 10 at its lower end in the usual manner, or which may be provided with the free steam exhaust arrangement described and claimed in my Patent No. 887,634 dated May 12, 1908. One or more of these tail pipes may be employed, as may be desired.

In the modification shown in Fig. 2, the head 11 of the steam pipe is of somewhat different form, being preferably a part of the casting 12 which forms the lower section of the inclosing wall of the condensing chamber.

It will be seen that the steam will be discharged from the openings in the upper ends of the steam inlet pipes into the falling water discharged from the cups or baffles, so that a complete condensation of the steam will take place.

It will be obvious that the form of the discharge head of the steam pipe may be changed in various ways; and that any suitable arrangement of means for producing the water spray may be employed.

I claim:

1. A barometric condenser having a suction pipe connected with the upper portion of its condensing chamber, a steam inlet pipe extending vertically upward through the bottom wall of the condenser and terminating within said chamber, and means for discharging water into said chamber intermediate of the upper end of the steam pipe and of the point of connection of the suc-

tion pipe, the suction pipe acting to create a counter current of steam upwardly through the discharged water; substantially as described.

5. 2. A barometric condenser having a suction pipe connected with the upper portion of its condensing chamber, a steam inlet pipe extending vertically upwardly through the bottom wall of the condenser and terminating within said chamber, means for discharging water into said chamber intermediate of the upper end of the steam pipe and of the point of connection of the suction pipe, the suction pipe acting to create a counter current of steam upwardly through the discharged water, and said pipe having 10 means at its upper end for preventing the discharge of water thereinto; substantially as described.
- 15 3. A barometric condenser having a suction pipe connected with the upper portion of its condensing chamber, a steam inlet pipe extending vertically upward through 20 of water; substantially as described.
4. A barometric condenser having a steam inlet pipe extending vertically upwards into the condensing chamber and terminating with a laterally perforated or slotted head, and a tail pipe connected to the lower portion of the condensing chamber to one side of the steam pipe; substantially as described.

In testimony whereof, I have hereunto set my hand.

AXEL H. HELANDER.
